LOCKING DEVICE FOR THE DRAWBAR COUPLER KEYS OF RAILROAD DRAFT GEARS

Harry N. Juel, John A. Schroeder, and Andrew W. Bower, Denver, Colo.

Application April 8, 1947, Serial No. 742,084

5 Claims. (Cl. 85—5)

1

This invention relates to a locking device for the draw bar coupler keys of railroad draft gears. Many railroad accidents are caused by the coupler keys working loose from the draw bars of railroad cars. Many fastening devices have been used to retain the coupler keys in place. None of these have been permanently satisfactory, due to the fact that they shear or wear away and drop from the coupler keys.

The principal object of this invention is to provide a fastening or locking device for the coupler keys which will insure the latter remaining in place permanently.

Another object of the invention is to provide a fastening device which will still retain the coupler key in place even though parts of the fastening device have become broken or lost.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawings:

Fig. 1 is a perspective view, illustrating a typical railroad draw bar and coupler key with the invention in place thereon;

Figs. 2, 3, and 4 are detail, perspective views of various elements employed in the improved locking device;

Fig. 5 is an enlarged cross-section, taken on the line 5—5, Fig. 1; and

Fig. 6 is a bottom view of the device.

In Fig. 1 a conventional draw bar is illustrated at 10 with its coupler at 11 and coupler key at 12. The invention is designed to prevent the coupler key 12 from withdrawing from the draw bar 10.

The improved locking device comprises an elongated, somewhat rectangular sleeve 13 of a size and shape to fit over the extremity of the key 12. The sleeve 13 is held in place by means of a locking pin 14, which in turn is locked in place by means of a retainer key 15.

The opening in the sleeve 13 has a height equal to the thickness of the coupler key 12, plus the thickness of the retainer key 15. The top of this opening is provided with an elongated indentation 16 designed to receive an elongated head 17 formed on the pin 14. The bottom of the opening in the sleeve 13 contains a notch 18 opening to the front face of the sleeve and designed to receive the shank of the pin 14.

Two keyholes 19 and 20 are formed in the sides of the sleeve 13 at the bottom thereof for receiving the retainer key 15. The pin 14 is notched across its forward face, as shown at 21, for the

2

passage of the key 15. The key 15 is provided with an upturned head 22 at one extremity, and with a thin, bendable end 23 at its other extremity.

A vertical hole 24 is drilled through the coupler key 12 to receive the pin 14. The locking device is installed by dropping the pin 14 into the opening 24, then passing the sleeve 13 thereover. Since the opening in the sleeve has a greater height than the thickness of the key 12, the sleeve may be raised on the key to allow it to be passed over the head 17 of the pin 14 while the shank of the pin 14 moves into the receiving notch 18.

When the sleeve is in place over the pin, the former drops into contact with the key 12, with the head 17 of the pin resting in the receiving socket 16. The retainer key 15 is now driven through the keyhole 19 beneath the coupler key 12, through the notch 21 in the pin 14, and through the opposite keyhole 20. The bendable end 23 of the key 15 is then bent downwardly and inwardly.

The keyhole 20 is opened through the bottom of the sleeve 13 to allow the key to bend downwardly at this point without projecting beyond the side of the sleeve 13, as shown in Fig. 5.

It will be noted that this permanently and securely locks the coupler key 12 in place. Outward movement of the sleeve 13 is resisted at the top by the head 17, and at the bottom by the retainer key 15, which bears against the pin 14. There is practically no strain or wear upon the retainer key 15. However, should this key, through defects in manufacture or for some other reason, become displaced, the sleeve 13 will still retain its position on the coupler key 12, due to the embedment of the head 17 in the socket 16. Therefore, a double safety feature is provided by the improved locking device.

It will be noted that the head 17 is non-circular, and that the socket 16 has a similar non-circular contour. This is for the purpose of automatically aligning the notch 21 in the pin 14 with the path of the key 15.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A locking device for the coupler keys of railroad draw bars comprising: a sleeve adapted to receive and surround the extremity of a horizontal coupler key; a retaining pin passing vertically through said key within said sleeve, said sleeve having an internal socket for receiving the head of said pin; and a retainer key passing horizontally through said sleeve below said coupler

key and transversally of the latter, said retainer key engaging a notch in the side of said pin and acting to prevent upward movement of said sleeve so as to retain said head in said socket.

2. A locking device for the coupler keys of railroad draw bars comprising: a sleeve adapted to receive and surround the extremity of a horizontal coupler key; a retaining pin passing vertically through said key within said sleeve, said sleeve having an internal socket for receiving the head of said pin; a retainer key passing horizontally through said sleeve below said coupler key and transversally of the latter, said retainer key engaging a notch in the side of said pin and acting to prevent upward movement of said sleeve so as to retain said head in said socket; and a bent extremity on said retainer key for retaining the latter in place.

3. A locking device for the coupler keys of railroad draw bars comprising: a T-headed pin passing vertically through said coupler key; a sleeve surrounding said coupler key and said pin, said sleeve having an internal indentation receiving the T-head of said pin; and a retainer key passing through the sides of said sleeve and between said coupler key and said sleeve to retain said head in said indentation.

4. A locking device for the coupler keys of railroad draw bars comprising: a T-headed pin passing vertically through said coupler key; a sleeve surrounding said coupler key and said pin, said sleeve having an internal indentation receiving the T-head of said pin; a retainer key passing

through the sides of said sleeve and between said coupler key and said sleeve to retain said head in said indentation, said pin having a notch in its side for the passage of said retainer key; a head on one extremity of said retainer key; and a bent end on the other extremity of said key, locking the latter in place.

5. A locking device for the coupler keys of railroad draw bars comprising: a T-headed pin passing vertically through said coupler key; a sleeve surrounding said coupler key and said pin, said sleeve having an internal indentation receiving the T-head of said pin; a retainer key passing through the sides of said sleeve and beneath said coupler key to retain said head in said indentation, said pin having a notch for the passage of said retainer key; a head on one extremity of said retainer key; and a bent end on the other extremity of said key, locking the latter in place, said sleeve being notched for the reception of said bent end.
